UNITED STATES PATENT OFFICE

OWEN GILES, OF LONDON, ENGLAND

EXHAUST VENTILATOR

Application filed July 1, 1929, Serial No. 375,205, and in Great Britain July 14, 1928.

This invention relates to exhaust ventilators of the kind comprising an uptake chamber the top of which communicates with downtake chambers provided with outlets that discharge into the exhaust passages of the ventilator, and has for its object to improve the construction and arrangement of such ventilators so as to increase the efficiency thereof and to adapt the same for use with railway and other vehicles in order to prevent the entry of sparks, rain, blacks, dust etc., into the vehicle through the ventilator.

According to this invention the casing of an exhaust ventilator of the kind referred to is internally subdivided by a pair of horizontally disposed perforated platforms so as to form upper and lower air spaces, and by vertical baffle plates arranged between such platforms so as to form inner and outer chambers, of which the inner chamber comprises the central uptake, while the outer chamber comprises the exhaust passages and openings and the downtake chambers which communicate with the central uptake through the upper air space and are provided with outlets that discharge into the exhaust passages of the outer chamber.

The invention is illustrated in the accompanying drawings wherein similar references indicate like parts.

Figure 1 is a side view in half section on the line I—I (Figure 2), and Figure 2 a sectional plan on the line II—II (Figure 1), while Figure 3 is an end view in half section on the line III—III (Figure 4), and Figure 4 a sectional plan on the line IV—IV (Figure 3), of one construction of exhaust ventilator in accordance with the present invention.

Figure 5 is a side view in half section and Figure 6 a sectional plan on the line VI—VI (Figure 5) of a modified construction of exhaust ventilator in accordance with the present invention.

As indicated in the drawings the ventilator consists of a casing *a* furnished with vertical exhaust openings *b* and mounted on a base plate *c* that is perforated as indicated at *d* to form the uptake of the ventilator.

The casing *a* is internally subdivided by

horizontally disposed perforated upper and lower platforms *e* and *f* and vertical baffle plates *g* and *m* which are fitted between such platforms so as to form the central uptake chamber *h* and the downtake chambers *k* and exhaust passages *o* of the ventilator.

The platforms *e* and *f* are arranged in the casing *a* so as to form upper and lower air spaces *p* and *q* which are connected by the central uptake chamber *h*.

The lower air space *q* is connected to the inlet of the ventilator through the perforated base plate *c*, while the downtake chambers *k* are connected to the upper air space *p* through corresponding openings *r* formed in the upper platform *e*, the lower ends of the downtake chambers *k* being closed by the lower platform *f* as indicated at Figures 1 and 3.

The baffle plates *m* form the inner walls of the downtake chambers *k* and are disposed between the upper and lower platforms *e* and *f* parallel with the baffle plates *g* so as to form the exhaust passages *o* which terminate in the vertical exhaust openings *b* in the outer casing, the baffle plates *m* being slotted to form the vertical outlets *n* through which the downtake chambers *k* are connected to the exhaust passages *o*.

The improved ventilator may be designed and constructed so that the exhaust openings are arranged either laterally or in each face of the ventilator casing according to requirements. Thus, in the construction illustrated at Figures 1 to 4 the casing *a* is designed so that the exhaust openings *b* are arranged in pairs laterally of the casing. In this construction flat vertical baffle plates *g* and *m* are employed to form a rectangular uptake chamber *h* and straight exhaust passages *o* the ends of which terminate in the lateral pairs of exhaust openings *b*.

The purpose of the air space *q* is to serve as a dust trap when no particular air currents are passing through the ventilator, as for instance, when the vehicle is stationary and there is no wind. When air is exhausted through the ventilator the updraft sets up eddy currents in the lower space *q*, by which any dust and the like, lodged therein, is caught up and swept out of the ventilator.

In the construction illustrated at Figures 5 and 6 the casing *a* is designed so that the exhaust openings *b* are arranged in each face of the casing. For this purpose curved baffle plates *g* are employed to form a diamond shaped uptake chamber *h*, while the baffle plates *m* forming the inner walls of the downtake chambers *k* are curved concentrically with the baffle plates *g* so as to form curved exhaust passages *o* that terminate in the exhaust openings *b* in adjacent sides of the casing, such openings being vertically subdivided by the corners *v* of the central uptake chamber, as indicated at Figure 6.

In the construction illustrated in the drawings the ventilator is formed of sheet metal and is provided with a flanged base plate *c* that can be readily secured to the end of an uptake shaft or opening of a railway vehicle or other structure by means of screws or in any other convenient manner.

When the ventilator is in use air currents are directed through the exhaust passages *o*, past the outlet apertures *n* and rapidly exhaust foul air through the ventilator, while the arrangements of the outlet openings in the inner walls *m* of the downtake chambers effectively prevents the entry of sparks, blacks, rain, dust and other impurities into the vehicle or structure to which the ventilator is fitted.

I claim:

1. An exhaust ventilator of the kind referred to, comprising a laterally perforated casing provided with a perforated base and subdivided internally by a pair of horizontally disposed platforms into upper and lower air spaces, and by vertical baffle plates, between such platforms, into inner uptake and outer downtake chambers and exhaust passages, the latter having openings communicating with the downtake chambers, and the uptake communicating with the downtake through the upper air spaces.

2. An exhaust ventilator according to claim 1, in which the vertical baffle plates are arranged in parallel relation between the upper and lower platforms and form transverse exhaust passages leading from the downtake chambers to the exterior of the ventilator through lateral openings in the casing substantially as hereinbefore described.

In testimony whereof I affix my signature.

OWEN GILES.
